UNITED STATES PATENT OFFICE.

WILLIAM E. EASTMAN, OF BOSTON, MASSACHUSETTS, ASSIGNOR TO THE AMERICAN FREIGHT CAR HEATER COMPANY, OF PORTLAND, MAINE.

APPARATUS FOR HEATING FREIGHT-CARS.

SPECIFICATION forming part of Letters Patent No. 269,189, dated December 19, 1882.

Application filed August 4, 1882. (No model.)

To all whom it may concern:

Be it known that I, WILLIAM E. EASTMAN, a citizen of the United States of America, residing at Boston, in the county of Suffolk and State of Massachusetts, have invented certain new and useful Improvements in Apparatus for Heating Freight-Cars; and I do hereby declare the following to be a full, clear, and exact description of the invention, such as will enable those skilled in the art to which it appertains to make and use the same, reference being had to the accompanying drawings, and to letters or figures of reference marked thereon, which form a part of this specification.

The object of my invention is to provide additional improvements to former inventions (for which Letters Patent have been granted to myself, C. Henry Kimball, and Charles H. Murch, and numbered and dated as follows: No. 247,028, September 13, 1881, No. 248,924, November 1, 1881, and No. 253,521, February 14, 1882, the latter issued to myself alone,) whereby I may keep an even temperature in a freight-car for a given number of days without the attendance of a fireman, the heat being increased or diminished automatically, if any change of temperature of the atmosphere surrounding the car takes place, and whereby a great saving of fuel is accomplished, none being consumed except what is absolutely necessary to keep an even temperature inside the car. I attain these objects by the arrangement and construction illustrated in the accompanying drawings, in which similar letters and figures refer to similar parts throughout the several views.

Figure 1 is a perspective view of car complete. Fig. 2 is a longitudinal section through line *y*, Fig. 3. Fig. 3 is a bottom plan, showing smoke-pipes and ceiling. Fig. 4 is a perspective view of the heater or stove with the governor *G* and faucet attached thereto. Fig. 5 is a vertical section of the heater or stove when burning, and also shows the governor and faucet not in section. Fig. 6 is a transverse section of the governor, (through line *xx*, Fig. 7,) showing the wings of the valve and the induction port or opening 16 and the eduction port or opening 17. Fig. 7 is a vertical section of the governor. Fig. 8 is an end view of the oil-tank, showing its filling-tube *d* and the glass *e*, through which the height of oil in the

tank may be ascertained by sight. Fig. 9 is a transverse horizontal section of the heater or stove through the line *xx*, Fig. 5.

The external appearance of a car built and furnished with a heater in accordance with my invention is shown in Fig. 1, the only difference from an ordinary freight-car being the oil-tank *b*, box or chamber *c*, and cowls *a a*.

In Fig. 2, *f* is the stove or heater inclosed in the box or chamber *C*. *g g* are smoke-pipes running in both directions to the ends of the car in spaces formed by the floor, the sills, and the ceiling *s*, Fig. 3, thence upward between the outer wall of the ends of the car and a lining, *k*, which extends across the ends as well as along the sides of the car, finally discharging the smoke and gaseous products of combustion above the roof of the car from the cowls *a a*. *h* is a stop-cock or faucet for shutting off at will the flow of fuel from the tank *b* to the heater *f*. *G* is the automatic device or governor for controlling the flow of oil. It is shown in detail and in section in Fig. 7, and will be more particularly described hereinafter. *j* is the door to the heater. *22* are removable stoppers for allowing the discharge of soot when the smoke-flues are being cleaned. *k k* show the inside lining of the car, by which air-spaces and passages for hot air are formed entirely around the contents of the car. *n* is the tube through which the liquid fuel is supplied from the tank *b* to the heater *f*. *o* is the ordinary truss for strengthening the car. *p p* are openings or holes through the lining *k*, to allow warm air from between the walls and lining to enter the car at about the top level of the contained freight.

In Fig. 3, *q q* are holes or openings through the outside sills of the car, to allow warm air from the flues *r r* to pass to the spaces formed along the sides of the car by the walls and the lining *k k*, Fig. 2. *r* shows the hot-air flues which convey the heated air from the chamber *c* to the ends and the sides of the car, the ceiling *s* having been removed. At *g* are seen the smoke-pipes, indicated at the right-hand end by dotted lines. *t t* are the ordinary draw-bars.

In Fig. 4, *Z* is the base of the heater, forming a drip-pan for safety. *1* is the draft-opening above the oil basin or pan, extending entirely

around the flame, which burns in a circle. 3 is a draft-opening connecting with the drip-pan and hollow cylinder 5, as will be more fully described in connection with Fig. 5. 4 is a brass tube surrounding an iron tube, the two being connected at their upper ends by the metallic pin 4, leaving the brass or outer tube, *i*, free at its lower end to operate the valve by its expansion and contraction, as is more fully set forth in connection with Fig. 7.

In Fig. 5, Z is the drip-pan. 5 is the inner cylinder of the burner, and 10 the outer cylinder. The inside of 10 and the outside of 5 are turned true, and when they are put together form the annular or tubular passage 6, through which the liquid fuel passes to the flame. The cylinder 5 is hollow and extends above the cylinder 10. A current of air constantly passes up through cylinder 5, and is deflected by the concave disk 7, which is supported by the stud 8, and thus a supply of air is furnished to the inside of the circular or Argand flame, while a supply for the outer side comes in through the clear space 1. 9 is a copper rim, or, more properly, the outer half of a hollow ring. The opening in its center allows the flame to pass to the main part or drum of the heater. 11 is a shallow copper pan, with a threaded hole through the center large enough to allow of its being screwed down a little distance upon the outside of cylinder 10, which is also threaded for a short distance upon its outer surface at its upper end, as is clearly shown in Fig. 5. In other words, the shallow pan 11 has rising from its center the cylinders 5 and 10, with the tubular passage between them, and it is held firmly and closely to 10 by the threaded ring N, which screws down upon it after the manner of a check-nut. Packing may be inserted between this threaded ring or check-nut and the pan to prevent leakage of oil from the pan down the outside of the cylinder 10. From the surface of this pan the oil burns. There may be nothing but the naked pan; but in practice, for ease in starting a fire, I prefer to use a mat therein of asbestos or other non-combustible absorbent material. It will, however, be observed that this is in no sense a wick, as the oil, is after the fire is well started, in a state of ignition before reaching it, and it does not furnish fuel to the flame. An annular space, 12, is beneath the oil-pan 11, and plays an important part in keeping the heat from the under side of the pan from being conducted to cylinder 10. This space also furnishes a hot-blast to the flame as it receives cool air through openings 31, and furnishes hot air to the flame through numerous holes or openings near the periphery of and through the oil-pan 11. 13 is an opening through the bottom of the drip-pan to allow of the escape of oil in case of accident. Suitable openings through the bottom of chamber *c* furnish air for combustion and for circulation in the car. 14 shows the flame. 15 is an opening for the exit of smoke. There are two of them, as is shown in Fig. 3.

In Fig. 6, which, as before stated, is a horizontal section of the governor G, (through line *xx*, Fig. 7,) 16 shows the induction-opening for fuel; 17, the eduction-tube opening, and 18 the valve-stem, in form of a cross.

In Fig. 7, 16 is the induction and 17 the eduction openings for fuel, as shown in Fig. 6. 20 is the valve. 21 is the coil-spring for raising the valve. 22 is a thin diaphragm of metal, placed over and resting upon the valve, but not joined thereto. Its function is to make an oil-tight chamber, in which the valve operates. The periphery of this diaphragm rests upon a ring of suitable packing material, 23, and is forced down thereon by the screw-top 32. 24 is the inner or iron tube, and *i* the outer or brass tube. 25 is a movable piston of metal inside the iron tube 24, extending only a short distance up from its lower end. 26 is a metallic key passing loosely through a vertical slot in the iron tube 24, but fitting tightly in piston 25. 27 is a collar at the lower end of the brass tube *i*. 28 is a check-nut for holding the unequal-expansion combination in position when once adjusted, said adjustment being effected by screwing the tube 24 to a greater or less extent into screw-top 32.

In Fig. 8, which is an enlarged view of the end of the fuel-tank *b*, *d* is the filling-tube, and *e* the gage-glass.

In Fig. 9, 8 is the stud carrying the deflector 7. 5 is the inner cylinder. 6 is the annular space. 10 is the outer cylinder. N is the threaded check-nut ring. A is the mat, of non-combustible absorbent material; and 11 is the oil-pan, G the governor, and *h* the faucet or stop-cock.

The fuel which I use is a liquid hydrocarbon, preferably common kerosene-oil, and is contained in the cylindrical tank *b*. The oil descends by gravity through the tube *n*, stop-cock *h*, and governor G to the heater *f*, and is there consumed. The heat generated is conveyed by currents of air to all parts of the car through flues or passages formed by ceiling beneath the sills and linings inside the studing of the car.

The operation of the heater and the governor is as follows: The stop-cock *h* is opened and a small quantity of oil is allowed to flow up through the tubular space 6 into the oil-pan 11, where it is ignited. The flame is thereafter under control of the governor. The distinctive feature of this governor which I claim to be new is that it is not intended to keep the flame of constant volume or intensity, but to vary it according to the temperature outside the car. The tube of iron, 24, is rigidly fastened to the valve-box and expands upward. The brass tube *i*, being fastened rigidly to the upper end of the tube 24 by the pin 4, must expand (and to a greater degree than the iron tube) downward. This unequal expansion operates the piston 25 by pressure through the collar 27 upon the key 26, and forces the diaphragm 22 downward. This in turn forces the valve 20 nearer its seat and diminishes the flow of oil.

Contraction, on the contrary, relieves the pressure upon the diaphragm and valve and allows the spring 21 to open the valve and increase the flow of fuel.

5 If a heater attached to a car be started when the temperature of the outside air be at zero, a flame of large volume will be maintained, because the outside air entering the chamber will so cool the governor as to allow the valve 10 to remain open to almost its full extent; but if the car be attached to a train and run to some place where the weather is warmer, the volume of flame will be diminished, because the air entering the chamber *c* will cause an 15 expansion in the governor and reduce the quantity of fuel supplied.

The governor may be located outside the chamber *c*, but for security against accidental damage I locate it therein, and also for the 20 further reason that a double action is obtained, for in case of clogging of the valve the diminished heat within the heater allows a contraction which will free the valve of an obstruction. I have not shown the valve located outside the chamber *c*, as I have deemed it to be 25 unnecessary.

The distinctive feature of the heater, and one which alone renders it practical for use in a car or other moving vehicle, is that it has 30 no wick. Neither is it a vapor-burner. The hydro carbon oil is burned, as such, from a pan, a part only of the surface, as heretofore set forth, being covered with a non-combustible absorbent mat in form of a ring. As there 35 is no wick, the jolting of the car does not interfere, as is the case when one is used, in which case the wick gets out of adjustment by reason of being shaken down and by consumption. No trimming of this burner is necessary, and as it is not a vapor-burner, special 40 care has been taken in its construction to prevent the vaporization of the liquid fuel before reaching the burning-surface of the oil-pan.

Having thus fully described my invention, 45 I claim and desire to secure by Letters Patent the following:

1. A wickless heater, an automatic governor, and a fuel-reservoir, connected with each other by a fuel-supply pipe, the said automatic governor being so located as to be beyond the reach of the fire in the heater, substantially as described.

2. A wickless heater, an automatic governor, and a fuel-reservoir, connected with each other by a fuel-supply pipe, the said automatic governor being so located as to be beyond the reach of the fire in the heater, in combination with the hot-air flues formed by the flooring, the ceiling, and the sills of a car, substantially as described.

3. An automatic governor, consisting essentially of an unequal-expansion pair or combination and a valve inclosed within a hermetically-closed valve-chest, in combination with an elevated reservoir containing liquid fuel, which flows therefrom at a rate determined by the temperature of the aforesaid governor.

4. An automatic governor operating by unequal expansion and contraction of certain of its parts, so located with reference to a heater 70 and a fuel-reservoir (to neither of which it is connected except by a fuel-supply pipe) as to be beyond the reach of the fire in the heater and subject to currents of air at atmospheric temperature, substantially as described. 75

5. The unequal-expansion pair, the members of which are attached to each other and the whole to the valve-chest, and operating the piston, substantially as described, and for the purpose specified, in combination with an elastic diaphragm, a valve, and a stove or heater for burning liquid fuel. 80

6. A heater or stove for burning liquid fuel without a wick, in combination with an automatic governor which controls the supply of 85 fuel by the operation of an unequal-expansion pair or combination upon a valve through the medium of an elastic diaphragm, substantially as described.

7. A wickless stove or heater for burning 90 liquid fuel and not vapor, attached to a movable vehicle, the absence of wick preventing derangement by jarring, as specified, in combination with an automatic governor consisting essentially of an unequal-expansion pair or 95 combination operating a valve within a hermetically-closed valve-chest through the medium of an elastic diaphragm, substantially as described.

8. An automatic governor, consisting essentially of an unequal-expansion pair or combination and a valve located within a hermetically-closed valve-chest, motion being communicated from said unequal-expansion pair to said valve through the medium of an intervening 100 elastic diaphragm, which is attached to neither the valve nor the expansion pair, substantially as described.

9. A wickless stove or heater burning liquid fuel and not vapor, attached to a movable 110 vehicle, the absence of wick preventing derangement by jarring, as specified, in combination with an automatic governor consisting essentially of an unequal-expansion pair or combination and a valve within a hermetically-closed valve-chest connected with an 115 elevated reservoir containing liquid fuel, which flows therefrom at a rate determined by the temperature of the aforesaid governor, substantially as shown and described. 120

10. A heater or stove for burning liquid fuel without a wick, in combination with an automatic governor consisting essentially of an unequal-expansion pair or combination and a valve within a hermetically-closed valve-chest 125 connected with an elevated reservoir containing liquid fuel, which flows therefrom at a rate determined by the temperature of the aforesaid governor, substantially as described.

11. A heater or stove for burning liquid fuel 130 without a wick, in combination with an automatic governor consisting essentially of an unequal-expansion pair or combination and a valve within a hermetically-closed valve-chest

connected with an elevated reservoir containing liquid fuel, which flows therefrom at a rate determined by the aforesaid governor, and the hot-air flues formed by the sills, the floor, and the ceiling of a car, substantially as described.

12. The oil-pan from the surface of which the fuel is burned, in combination with a

valve within a hermetically-closed valve-chest operated by an unequal-expansion pair or combination, substantially as described.

WILLIAM E. EASTMAN.
